INVENTOR

Walter Olcott
(Hank Sutherland)

ATTORNEY.

UNITED STATES PATENT OFFICE.

WALTER OLcott, OF SOUTH MANCHESTER, CONNECTICUT.

GREEN-CORN IMPLEMENT.

1,414,372.

Specification of Letters Patent.

Patented May 2, 1922.

Application filed January 6, 1922. Serial No. 527,316.

To all whom it may concern:

Be it known that WALTER OLcott, a citizen of the United States, residing at South Manchester, in the county of Hartford and 5 State of Connecticut, has invented certain new and useful Improvements in Green-Corn Implements, of which the following is a specification.

This invention relates to a green corn 10 implement. Among the objects of the invention are the provision of a tool of this character which can be inexpensively made and which can be easily and readily operated in performing one of several functions, 15 one of these desirably, being in the present case the cutting off of the tops of the kernels from the cob, and another being the cutting through the kernels and subsequently squeezing the contents of the kernels therefrom.

20 In the drawings accompanying and forming part of the present specification I have shown in detail one of the several forms of embodiment of the invention which to enable those skilled in the art to practice the 25 same will be set forth fully in the following description. I am in no sense restricted to this showing. I may depart therefrom in a number of particulars within the scope of the invention defined by the claims following 30 said description.

Referring to said drawings:—

Figure 1 is a face view of the implement as seen from one side thereof.

Fig. 2 is an end elevation as viewed from 35 the right in Fig. 1.

Fig. 3 is a side elevation.

Figs. 4 and 5 are perspective views showing the different actions of the implement upon an ear of corn.

40 The implement involves a blade member such as 2 and which may be of sheet steel or other proper material. At its back end it has a tang 3 fitting a notch or kerf 4 in the forward end of the handle 5 which may be 45 of wood or other proper substance. Usually a rivet 6 is provided to hold the blade member in rigid assembled relation with the handle 5, the rivet extending through the tang 3.

50 The body of the blade member 2 is as shown, practically flat and has along opposite edges and virtually co-extensive therewith the flanges 7 and 8. The flange 7 is desirably but not imperatively at practically 55 right angles to the body of the blade member, while the flange 8 is at an obtuse angle

thereto, the edges of both flanges 7 and 8 being straight.

The blade member 2 has as shown at one side of its longitudinal, median line the 60 transverse slits 9 and the connecting slit 10 the stock 11 within said slits being bent from the body of the blade member to produce the cutting blade 11, the free portion of which is beveled to produce a cutting edge. 65 The free edge of the cutting blade 11 is slightly back of the flange or lip 7 and is in parallelism therewith.

The blade member 2 in adjacency to the bent or curved flange or lip 8 has a longitudinal row of practically segmental slots 12 the stock from which produces a row of longitudinal and somewhat triangular teeth 13 adjacent to the flange or lip 8, the forward sides of these teeth being beveled to 75 produce cutting edges.

In Figs. 4 and 5 I show the different actions of the implement. In Fig. 4 the flange 7 is at the front, the blade member 2 resting upon the kernels, the tops of some which 80 have already been cut off as the implement is moved toward the forward end of the ear of corn. On this forward movement the blade member will cut off the kernels from several rows as the blade member is moved 85 forwardly and the flange or lip 8 will positively dislodge the kernels thus cut off and also the pulp.

In Fig. 5 the position of the blade member is exactly reversed, the cutting blade 90 11 at this time being up and not in action, the same observation applying to the flange or lip 8. In this case as the blade member 2 is advanced, the forward cutting edges of the teeth cut transversely through the kernels of corn and the flange 7 or rather its straight edge, squeezes the substance from the kernels.

It will be clear from the foregoing description taken in connection with the annexed 100 drawing that the implement involves a handle provided with a blade member which has on one side of it a blade and is provided at the rear of the blade with a squeezing portion which as shown is in the form of a 105 flange, the blade member having on its opposite side a row of teeth back of which is a second squeezing portion also in the form of a flange, the two flanges extending practically in opposite directions.

What I claim is:—

1. An implement of the class described

comprising a handle provided with a blade member, the blade member having at one side thereof a blade and provided at the rear of the blade with a squeezing portion, the blade member having on its opposite side a row of teeth and also having back of the teeth a squeezing portion.

2. An implement of the class described comprising a handle, provided with a blade member, the blade member having on one side thereof a blade and provided at the rear of the blade with a flange constituting a squeezing portion, the blade member having on its opposite side a row of teeth and also having back of the teeth a second flange disposed approximately oppositely to the other flange.

3. An implement of the class described

comprising a handle provided with a blade member having cut therefrom a blade which is disposed on one side thereof and the cutting edge of which is at one side of the longitudinal median line of the blade member, the latter having on the same side as the blade, a flange constituting a squeezing portion, the opposite side of the blade member having a row of teeth, at the opposite side of said longitudinal median line and also having on the same side as the teeth a flange, the two flanges being located at opposite sides of the longitudinal median line.

In testimony whereof I affix my signature.

WALTER OLCOTT.

In presence of—

MARY F. LONG,
HEATH SUTHERLAND.
